UNITED STATES PATENT OFFICE.

ERNEST O. LINTON, OF INDIANA HARBOR, INDIANA, ASSIGNOR TO LINTON GASOLINE PROCESS COMPANY, OF CHICAGO, ILLINOIS, A CORPORATION OF DELAWARE.

CONTINUOUS METHOD OF CRACKING HYDROCARBON OILS.

Application filed May 26, 1921. Serial No. 472,797.

To all whom it may concern:

Be it known that I, ERNEST O. LINTON, a citizen of the United States, residing at Indiana Harbor, in the county of Lake 5 and State of Indiana, have invented certain new and useful Improvements in Continuous Methods of Cracking Hydrocarbon Oils, of which the following is a specification.

10 My invention relates to a continuous method of cracking hydrocarbon oils and particularly heavy oils having an asphalt base, such as Mexican Panuco oil and asphaltic and semi-asphaltic fluxes.

15 Some of these oils contain considerable quantities of water, up to 10 or 12%. Such oil I first dehydrate by passing it through a still in which the water is removed by distillation, the hot oil being then preferentially fed directly in continuous flow into the main still of a special construction invented by me, in which the hydrocarbons having lower boiling points are distilled and cracked while in the vapor phase in the 20 heated upper portion of the still, the heavy asphaltic ingredients flowing off continuously from the bottom of the still.

25 The novelty of the invention resides in the gradual raising of the temperature of the heavy oil while flowing in a film or stream over heated surfaces within an externally heated still, whereby the vaporizable constituents are freely liberated under practically atmospheric pressure into the 30 highly heated spaces within the still and are then cracked.

35 A further feature of novelty, aside from the cracking step, is the manner in which the oil is heated to a temperature sufficient 40 to vaporize one or more ingredients by delivering it into a closed chamber having a perforated bottom and then causing it to flow over extended heated surfaces, contained within an externally heated still, and 45 arranged to provide a tortuous passage for the upwardly flowing vapors, thereby securing a thorough intermingling of such vapors.

50 The apparatus in which my process is carried out is shown in the accompanying drawings in which—

Fig. 1 is a diagrammatic showing of the entire plant;

Fig. 2 is a vertical section through the dehydrator or still; 55

Fig. 3 is a vertical section through the second still;

Fig. 4 is a plan view of the parts below the plane 1—1 of Fig. 2; and

Fig. 5 is a plan of the plate 5; 60

Fig. 6 is a detail showing the manner of connecting the plate 5 to the cones 14 or 40.

The plant, as a whole, is shown in Fig. 1. Crude oil is delivered by pipe 2 into a supply tank A from which it flows into a dehydrator B and then into the main still C located in a heating chamber D. The asphalt flows into tank E and the evolved vapors from the still into the condenser F and tank G, from which the condensate may be 65 delivered by pump H into storage tank I and therefrom into a second still J, connected at its bottom to a residuum tank M, and at its top to a condenser K from which the condensate flows into tank L. 75

Referring to Fig. 2, the dehydrator B and still C are enclosed within a closed brick setting N, having one or more stacks or exit flues, O, O, for combustion gases rising from the combustion chamber. D' 80 The dehydrator B consists of a shell 3 supported on I beams and spaced from the walls of the setting N, so that the hot gases pass around it.

The pipe 4 extends downwardly through 85 the top of the dehydrator into a receptacle 40 preferably conical, having a bottom or distributing plate 5, provided with a series of openings 6. Located below the openings 6 is an annular deflector 7 having notches 90 or openings 8 around its outer edge, through which the liquid flows on to the conical bottom wall 9 of the dehydrator. Flues 10 and 11, provided with dampers or valves (not shown), permit the introduction of air 95 to cool the hot ascending gases to the desired degree.

The water vapor and any other vapor which may have been formed are carried off through pipe 12 to a condenser. 100

From the dehydrator, the water-free oil flows through pipe 13 into the main still C, all parts of which are subjected to the hot gases coming from the combustion chamber. The still for convenience may be said to 105 have a lower or vaporizing section and up-

per or cracking section. The construction of the lower or vaporizing section of the still is substantially the same as the dehydrator, having a receptacle 14 with apertured distributing plate or bottom 15.

The oil and any formed vapors pass out through the apertures into the space below. The cover of this chamber may be omitted, but I prefer the construction shown, as the 10 more volatile hydrocarbon vapors are compelled to pass out through the openings and are thus directed into the stream of vapors rising around the outside of plate 15. The liquid oil drops on to the annular apertured 15 deflector 16, having openings 17 through which the oil flows on to the downwardly inclined bottom 42 where the removal of the volatile ingredients is completed and the heavy residue or asphalt flows out through 20 pipe 18 into tank E. The still body C has an annular flange 19, resting on I beams 20, supported on the walls of the heating chamber. Beneath the still is a deflector 21, consisting of a metal plate, covered with ganister 25 or other refractory material.

The still is heated by the hot gases coming from oil or gas burners 22, 22, of any suitable construction.

At the upper portion of the still, there is 30 a tower 23 into which the vapors from the body of the still pass through a contracted opening 24. The vapors expand through this opening into the tower, which is provided with a closed filling cylinder 25, carried by the pipe 13. The vapors are thus caused to pass into contact with the inner heated wall of the tower. The heating gases are deflected toward the tower by the inner wall of a closed sheet-metal chamber 26, the 40 dead air space within such chamber serving as a heat insulation. This chamber rests on supports 27 at the bottom and is secured at the top by bolts extending through the wall of chamber N. Manholes 28, 28 afford access to the dehydrator and to the still.

From the top of the tower, the vapors pass through pipe 29 to condenser F, which may be of any suitable construction, preferably such as is shown in my application 50 Serial No. 429,190, filed Dec. 8, 1920.

The distillate collected in tank G may be subjected to any suitable treatment in a separate plant, but I prefer to deliver it by means of pump H and pipe 30 to tank I, whence it flows into the second still J (see Fig. 3) located within a heating chamber K, which is provided with a burner 32 beneath the still and additional burners 33, 33 for heating the upper conical portion of 60 such still. Connected to the still and extending outside of the heating chamber, is a tower, through which passes the enlargement 35 of pipe 31, and from which vapors are delivered through pipe 36 to the final 65 condenser K. Pyrometers, T, T', T², T³, in-

dicate temperatures within the still and dehydrator, and thermometers T⁴, T⁵, indicate condenser temperatures.

The operation is as follows:

The crude oil, as for example, an asphaltic base oil, such as Panuco oil, is delivered through pipe 4 on to the hot bottom 5 of the receptacle 40, over which it flows in a thin layer, the liquid and vapor being delivered through the holes 6. The liquid oil drops on to and spreads over the annular deflector 7 and flows through the openings 8 on to the extended surface of the downwardly inclined bottom portion 9 and out through the pipe 13. The temperature of the combustion gases passing around the dehydrator, either with or without cooling by air coming through pipes 10 and 11 is kept at such a degree that the pyrometer T⁶ located on or near the bottom of the dehydrator indicates a temperature of 350° to 400° F. Under these conditions I find that substantially all the water may be removed from water-containing heavy asphaltic oils or fluxes.

The dehydrated oil may be treated separately, but I prefer to run it while still hot directly into a still of the construction above described.

The oil delivered through pipe 13 is pre-heated while passing through the tower 23, which is surrounded by and enveloped in the hot gases from the combustion chamber. The volatile constituents of the oil are driven off as it spreads out over the extended surfaces of the heated distributing plate 15, deflector 16 and inclined bottom 42 of the still, which is directly subjected to the hot gases of the combustion chamber. The metal parts within the still are heated by conduction of heat from the walls of the still and by the continuous passage therethrough or thereover of the heated vapors. The rate of distillation is such that substantially no pressure is developed in the still, and the lighter hydrocarbons are thus free to vaporize from the large surface of the film of oil into the open spaces within the still. The vapors pass upwardly through the central opening in the annular deflector 16 and around the edge of receptacle 14, the intermingled vapors then passing into contact with the hot upper portion of the still proper, and expanding through the opening 24 into contact with the hot wall of the tower 23, and are thus maintained in a superheated state and under cracking conditions until they leave the still. As an indication of the order of temperatures, which I have found to be applicable 115 in the treatment of Panuco oil and asphaltic or semi-asphaltic fluxes, the heat is so controlled that the pyrometers T indicate a temperature between 800°—850° F., usually about 820° F.; that the pyrometer T¹ 120

indicates about 875°; and the pyrometer T² at the top of the tower indicates from 900°-950° F.

The rate of flow of oil through the still 5 is so adjusted that there is no accumulation of asphalt or oil in the still, the vapors being driven off from a thin film of oil flowing over hot surfaces, while the liberated vapors passing upwardly over the heated 10 still and tower walls are subjected to a maintained temperature high enough to ensure thorough cracking, with the resulting formation of a vapor mixture which upon condensation yields a distillate of much less 15 specific gravity than the original oil.

For example from a heavy asphaltic flux of 12.3 Bé. there was obtained 64.5% of distillate of gravity 43.7 Bé., and 30% of asphalt. Upon distillation of this 43.7 Bé. 20 product there was obtained a 450 E. F. gasoline of 54.6 Bé. gravity, which constituted 37.6% of the original stock.

For subsequent distillations I prefer to employ the still illustrated in Fig. 3, and 25 described above, into which the distillate is run from the tank I. The still is gradually heated up to 500° F., the distillate being collected in one or more condensers K.

Any gases which are formed may be collected and disposed of in the usual manner. 30

While I have described in detail the apparatus which I have used in practice, modifications may be made within the scope of my invention.

35 I claim:

1. The method of cracking heavy hy-

drocarbon oils, which consists in passing such oil as a thin sheet or film in continuous flow over heated surfaces within an externally heated still chamber, whereby vaporizable constituents are freely liberated into the still spaces, and are there subjected to a cracking temperature, permitting the hot vapors to expand into a heated expansion chamber, subjecting the vapors therein 40 to further heating at a maintained cracking temperature, condensing the cracked vapors, and withdrawing the liquid residuum. 45

2. The process as claimed in claim 1, in which the vapors are subjected to the maximum temperature before leaving the expansion chamber. 50

3. The method as claimed in claim 1 in which the oil is first dehydrated by passing it as a thin sheet or film in continuous 55 flow over heated surfaces within an externally heated still chamber, and then delivered to the cracking still.

4. The method of treating heavy hydrocarbon oils which consists in passing such oil as a thin sheet or film in continuous flow over a heated surface in a closed chamber within an externally heated still, permitting the oil and generated vapor to flow therefrom, and commingling such vapor with 60 the vapors generated by the flow of the oil over a succession of heated surfaces also within said still. 65

In testimony whereof, I affix my signature.

ERNEST O. LINTON.
